US0D1077764S

(12) **United States Design Patent** (10) **Patent No.:** **US D1,077,764 S**
(45) **Date of Patent:** **** Jun. 3, 2025**

(54) **TELEVISION RECEIVER**

- (71) Applicant: **Samsung Electronics Co., Ltd.**, Suwon-si (KR)
- (72) Inventors: **Giljae Lee**, Suwon-si (KR); **Jangho Kim**, Suwon-si (KR); **Hee-Bong Kim**, Suwon-si (KR); **Sinwi Moon**, Suwon-si (KR); **Jin-Su Park**, Suwon-si (KR); **Kyudae Lee**, Suwon-si (KR); **Seungho Lee**, Suwon-si (KR)
- (73) Assignee: **SAMSUNG ELECTRONICS CO., LTD.**, Gyeonggi-Do (KR)
- (**) Term: **15 Years**
- (21) Appl. No.: **29/888,364**
- (22) Filed: **Mar. 30, 2023**

(30) **Foreign Application Priority Data**

Oct. 4, 2022 (KR) 30-2022-0040426

(57) **CLAIM**

The ornamental design for a television receiver, as shown and described.

DESCRIPTION

FIG. 1 is a front perspective view of a television receiver, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 3;

FIG. 10 is an enlarged view of the encircled portion 10 in FIG. 6;

FIG. 11 is an enlarged view of the encircled portion 11 in FIG. 8; and,

FIG. 12 is an enlarged view of the encircled portion 12 in FIG. 4.

The dot-dot-dash broken lines in FIGS. 3, 6, and 8-11 indicate the locations from which corresponding enlarged views are taken.

The dot-dash broken lines in FIGS. FIGS. 3, 6, and 8-11, define boundaries of the claimed design and form no part of claimed design.

(Continued)

The evenly spaced dashed broken lines illustrating portion of the television receiver form no part of the claimed design.
